ELECTRON DISCHARGE TUBE

Anton Lauer, Ulm (Danube), Germany, assignor to Telefunken Gesellschaft für Drahtlose Telegraphie G.m.b.H., Hannover, Germany

Application April 7, 1955, Serial No. 499,990

Claims priority, application Germany April 7, 1954

9 Claims. (Cl. 315—3.5)

This invention relates to the construction of the mounting of an electron discharge tube, such as a traveling wave tube, in which an electronic beam is guided and focused over a longer path from a cathode to a collector electrode by means of a magnetic field which is parallel to the axis of the tube, said field being set up by a permanent or electromagnet.

The new mounting is provided in such manner that the magnetic field can be aligned parallel with respect to the axis of the tube, i.e. this tube which is supported at its ends is adapted to be adjusted in its relation to the magnet energizing the magnetic field.

It is an object of the invention to provide a mounting of the tube so that at one of its ends the tube can be moved or swung in all directions, similar to a ball-and-socket joint action, while at its other end the tube is radially adjustable.

It is another object of the invention to provide means at the radially adjustable mounting to lock the tube in any adjusted position.

These and other important objects and advantageous features of the present invention will be apparent from the following detailed description and drawings, appended thereto, wherein merely for the purposes of disclosure non-limitative embodiments of the invention are set forth.

Fig. 1 is a longitudinal section through a first embodiment of the traveling wave amplifier tube according to this invention.

Fig. 2 shows a cross section through the tube of Fig. 1 at the collector end of this tube.

Fig. 2a illustrates a cross section through a portion of Fig. 2 along the line A—B.

Fig. 3 is a side view of another embodiment of the invention, shown partially in section.

Fig. 4 illustrates a perspective view of a portion, i.e. the annular spring contact assembly, of the tube shown in Fig. 3, parts of the assembly being broken away to better show the inner structure.

Fig. 5 is a longitudinal section through a portion of a modification of the new device.

As shown in Fig. 1, within the evacuated envelope 1 there is provided a discharge system which comprises an electron gun 2 arranged inside a cylindrical shield, a helical conductor or helix 3 and a collector electrode 4. The shield of the electron gun 2, together with two metal cylinders 5 and 6 and a metal member 7 surrounding the collector electrode 4, serves as coupling means.

The various parts of the tube are built into a grid comprising three ceramic rods 8, of which only two are visible in Figure 1. Inside this grid is positioned the helical conductor 3 between the coupling cylinders 5 and 6 in which the ceramic rods 9 are mounted. The ends of said helical conductor 3 are passed through openings in the coupling cylinders 5 and 6, and are directly connected with the shield surrounding the elec-

2

tron gun 2 and with the metal member 7 at the end of this traveling wave tube.

When the tube is in operation, there emanates from the beam generating system a sharply focused electronic beam which traverses the helix or delay line 3 and then impinges on the electron collector 4. To prevent this beam from spreading due to its space charge, there is provided, in a manner known per se, a magnetic coil 10 surrounding the tube. In order to avoid any bombardment of the helical conductor by electrons, the magnetic field energized by the coil 10 must be positioned parallel to the axis of the helical conductor 3, since the electrons travel in the direction of the lines of the magnetic field.

In order to avoid self-energization of such a tube, 15 there is provided on the ceramic rods 9 a damping means in form of strips 11 running in the longitudinal direction of these rods. The ends of these strips are bent outward, away from the helix 3, to assure reflection-less transmission, and these ends are thus diverted from the immediate field of the waves traveling along the helix 3.

The high-frequency waves to be amplified are supplied via a hollow tube conductor 12, while the amplified waves are taken off from a hollow tube conductor 13. The two hollow tube conductors 12 and 13 are rigidly 25 secured to one another by means of a metal cylinder 27 of non-ferro-magnetic material which is spatially separated from the discharge tube.

At the ends opposite to the connector sides, the two 30 conductors are adjustable by means of tuning slides 14 and 15 for maximum energy transmission from the high-frequency line to the terminal of the helix. The distance of the slides 14 and 15 from the axis of the tube amounts to about $\frac{1}{4}$ of the operating wave length. The operating voltage is supplied to the tube via the pin base fitting 16 and via a contact plate 18 attached to the cooling ribs 17 of the collector electrode 4. Consequently, the operating voltages for the electron gun 2 are fed via the pin base. The voltage for the helix is supplied via the metal cylinder 7, which is electrically connected to the wall of the hollow tube conductor 13 by means of an annular spring contact member 19 which will be described in detail below.

This annular spring contact 19 serving as bearing or support for the tube permits adjustments or movements 45 of the tube in all directions at the collector end of the tube. The pin base fitting 16 is connected to a cup-shaped member 20 with the aid of rivets, lugs, bolts or similar means. This cup-shaped member 20 engages with its flange 21 a tubular socket 22 which is attached to the hollow tube conductor 12 serving as input.

The cup-shaped metal member 20 is mounted on the threaded free end 24 of the socket 22 by means of a cap screw 23. Therefore, the position of this part of the mounting can be radially adjusted upon loosening 55 of the cap screw. By a radial shifting at this end, the tube is swung about the center point of the universal bearing 19 at its collector end 7. Since thereby the tube is angularly displaced from its former axis, the mounting 16 of the pin base fitting of the tube must be designed so as to be capable of taking up the resultant mechanical stresses without damage to the tube. The usual pin base 60 mountings for "Pico" tubes available in the market satisfy these requirements adequately and permit a turning of the tube by several degrees without causing impossibly high stresses in the tube socket. As a safety measure it is advisable to enclose the pin base fitting 16 with a protective casing 42, such as is shown at left in Figure 1.

With the afore-described arrangement according to the 70 invention a positioning of the magnetic field parallel to the helical conductor axis, which is necessary for the

effective operation of a tube, can be readily obtained in the following manner. After applying all required operating voltages, the cap screw 23 is slightly loosened and, by a radial displacement of the cup-shaped metal member 20, adjustment is made to a position in which the helical conductor carries a minimum of current. For this purpose, a measuring instrument is suitably inserted in the circuit of the helical conductor 3. After determining this optimum position, the cap screw 23 is tightened, so that a subsequent displacement of the tube from this position becomes impossible. Due to the universal adjustability of the tube assembly according to the invention, it becomes possible to adequately take care of any tolerances occurring in traveling wave tubes with regard to the axis of the helical conductor, such tolerances being unavoidable in the manufacture of these tubes. The device according to the invention makes it possible to reduce considerably the tolerance demands as to the axial position of the helical conductor.

In practice, it is desirable to fix the axial position of the tube in the socket. As shown in the embodiment of Fig. 2, an axial abutment is provided, which can most simply be associated with the universally turnable mounting member. In the example shown in Figure 2, a flange 25 is provided on the cup-shaped metal member 7 which is mounted universally turnable in the contact ring 19 consisting of a helical spring having its ends joined. This flange 25 engages an abutment on a tubular socket 26 in a wobble-plate manner, said socket being attached to the hollow tube conductor 13 at the output end of the tube. The helical spring 19 is lodged in an annular groove provided in the socket 26.

The inner diameter of this tubular socket 26 is made somewhat larger than the outer diameter of the member 7 of the traveling wave tube, so that the latter can be turned therein in all directions. Thus, the flange 25 of the metal part 7 may engage the wall of the tubular socket 26 at a particular point thereof depending on the angular position of the tube. For example, in Figure 2, part 7 of the tube is shown at a slightly downward angle with regard to the axis of the mounting, thus causing the member 7 to engage part 26 at a lower point near the outer edges of the two parts.

The universally adjustable mounting of the tube at its collector end is particularly advantageous, since this permits at this collector end a relatively simple coupling structure comprising the metal parts 6 and 7 which are connected to the wall of the hollow tube conductor 13. Therefore, any detuning caused during the axial adjustment of the tube at the places of contact with the input or output ends of the hollow tube conductors are less at the collector end than at the input end even in case of larger displacements. It is necessary to keep the detuning to a minimum particularly at the collector end, since any reflected wave energy might return to the tube and may cause undesired oscillations. This is not too critical at the input end, because waves reflected at that place can, at worst, return to the source or to the control generator. This source usually shuts off the input end of the hollow tube conductor without reflection, whereby a wave reflected at the input end travels to the source, or to the generator, without causing any disturbance.

Figure 3 illustrates another embodiment of this invention. The assembly corresponds generally to that shown in Figure 1, i.e. especially in similarity of construction of the mounting at the cathode end. The same reference numerals as in Fig. 1 are used for like parts in Fig. 3. The tube mounting and the collector end of the traveling wave tube are shown in section.

Coupling cylinder 6 surrounding the helix 3, and the metal member 7 surrounding the collector 4 are indicated in this sectional view. The collector 4 is mounted in the metal member 7 by means of a vitreous disk 28. A

cooling head 17, having a plurality of cooling ribs, and a contact plate 18 are attached to the collector 4.

It is assumed in this example, for the sake of simplification, that the axis of the helical conductor 3 coincides with the axis 29 of the traveling wave tube amplifier. The metal member 7 supporting the collector electrode 4 has a flange 25' similar to that shown in Figure 2, said flange being adapted to engage a socket 30 secured to the hollow tube conductor 13 at the output end in a wobble plate-like manner.

The electric connection comprises a contact ring consisting of spring elements 31 arranged annularly. The individual contact spring elements 31 are shaped like lamellas, similar to those known as "tulip contacts" conventionally used in short-circuiting slides for high-frequency lines. Such a contact ring is shown in Figure 4 in perspective view.

The helical conductor 3 is connected similarly as in the construction according to Figure 1, via the metal member 7 directly to the potential of the magnet socket of the traveling wave tube amplifier, which is grounded in the usual manner. To apply the operating voltage to the collector electrode 4, the mounting assembly is enclosed in a tubular metal cylinder 32 having an insulating member 33 covering the open end of this cylinder 32 housing the parts at the collector end of the tube. The insulating member 33 has an opening provided concentrically with respect to the axis of the traveling wave tube, a helical or compression spring 34 being placed in this opening. The spring is adapted to bear against the contact plate 18 of the traveling wave tube collector 4. A lead for the operating voltage is passed from the outside through the insulating member 33 to be connected to the spring 34.

In each of the traveling wave tube amplifiers shown and described in these examples, the mounting is designed in such a manner that the tube is introduced from the output end of the amplifier into the pin base mounting at the input end of the amplifier. For this purpose, the insulating member 33 in Figure 3 is held in the metal cylinder 32 by means of a bayonet-type fitting. Thus, by disconnecting this fitting it is possible to remove the insulating member 33 and to exchange the tube with the aid of a tube puller. Instead of removing the insulating member 33 it is possible to remove the metal casing 32. This has the advantage that the tube can be removed by gripping it at the cooling head now directly accessible, without the use of any tools.

It is expedient to provide the casing 32, just like cup member 20 at the input end, with ventilating holes to remove the hot air and to admit cool air. Furthermore, it is possible to provide larger openings in this member 32 and to direct a current of compressed air through the openings over the cooling ribs of the head 17 of the collector.

The use of the type of universally adjustable mountings shown in the foregoing examples is also desirable, as losses in high-frequency energy are prevented because the all around engaging contact rings assure a practically perfect electric connection between the wall of the hollow tube conductor 13 and the metal member 7 which is part of the coupling means, so that no high-frequency energy can escape via this mounting member.

Figure 5 shows another example of a radially adjustable mounting. It is designed for application to the cathode end of a traveling wave tube. The pin base fitting 16 is fastened to a metal plate 35. This metal plate is provided with relatively large holes 36 and 37 through which bolts are passed to be threaded into the tubular member 22 which is secured to a wall 40 of the hollow tube conductor 12 at the input of the tube.

To avoid the loss of high-frequency energy across the gap existing between the coupling cylinder 6 and the inner wall of the member 22, a so-called $\lambda/4$ choke is provided in form of an annular gap or slot 41 cut or

milled in this member 22, the length of said gap or slot amounting to $\frac{1}{4}$ of the operating wave length. Since such a choke constitutes a sufficient block for all practical purposes within a range of from $\frac{1}{8}$ to $\frac{3}{8}$ wave lengths, the escape of high frequency energy is prevented throughout an extended frequency range.

The proper adjustment of the tube with respect to the position of the magnetic field is obtained in the following manner. After loosening the bolts 38 and 39, the pin base fitting together with the plate 35 is radially displaced just as in the embodiment shown in Figure 1, and after determination of the optimum tube position the bolts 38 and 39 are tightened, thus locking the plate 35 rigidly in its position.

Thus, in the construction according to the invention, the tube is mounted in ball-and-socket joint fashion at one end, while the mounting at the other tube end is designed to permit radial adjustments. The abutment in the other embodiments of the invention is a flange and the engagement in the embodiment of Fig. 5 may likewise take place at a single place or point which can be provided at the input end of the tube. In the example, according to Figure 1, the pin base mounting 16 serves also as axial abutment for the tube. This is made possible by providing the hollow tube conductors in such a manner that, with complete insertion of the pin socket of the tube into the pin base fitting 16, the planes of the metal members 2, 5, 6 and 7 are in a position required for a transmission without reflection.

Although in accordance with the provisions of the patent statutes this invention is described as embodied in concrete forms and the principle of the invention has been explained together with the best modes in which it is now contemplated applying that principle, it will be understood that the elements and combinations shown and described are merely illustrative and that the invention is not limited thereto, since alterations and modifications will readily suggest themselves to persons skilled in the art without departing from the true spirit of the present invention or from the scope of the annexed claims.

I claim:

1. In a travelling wave system including an electron discharge tube having an elongated envelope having at one end an electron emissive source to emit an electron beam and having at the other end of the envelope a collector electrode to collect the electrons of said beam, said source and said collector electrode having a common axis therebetween, and said system including wave guide means having an envelope-receiving cylindrical portion located between mutually spaced hollow wave input and output conductors respectively having openings for receiving the source end and the collector end of the tube, and said system including magnet means secured in fixed relation around said cylindrical portion and setting up a magnetic field therewithin to focus said electron beam, said field having an axis corresponding substantially with the axis of the cylindrical portion, improved support means for positioning the tube in the cylindrical portion of the wave guide means comprising an annular bearing member on said tube axially adjacent to and precisely centered around the collector electrode; socket means attached to said output conductor at its opening and coaxial with said cylindrical portion and having annular means surrounding said bearing member and

maintaining it centered on the axis of the field; and mounting means attached to said input conductor at its opening and having adjustable means gripping said source end of said tube and being adjustably displaceable transversely of the axis of the field, whereby the collector electrode is supported on the axis of the field by said annular means and whereby said common axis can be oriented precisely parallel with the axis of the field by said adjustable means.

10 2. In a system as set forth in claim 1, said annular means in the socket comprising an annular series of spring means maintaining the bearing member on said tube substantially centered on the axis of the field while permitting tilting displacements of the member through small angles.

15 3. In a system as set forth in claim 2, said bearing member on the tube including at its outer end an outwardly extending flange adapted to engage the outer end of the socket and serving as an abutment to limit the axially inward penetration of the tube into the wave guide means.

20 4. In a system as set forth in claim 3, said collector electrode extending beyond the envelope adjacent said flange; a casing covering the socket and enclosing the collector electrode; and a compression spring supported in the casing by insulation means and compressed against the collector electrode, the spring maintaining the flange in engagement with the socket and the spring serving as an electrical connector for the collector electrode.

25 5. In a system as set forth in claim 2, said spring means comprising a helical wire spring having its ends connected to form a ring, and said socket having an internal annular groove receiving the wire spring and maintaining it in circumferential contact with said bearing member on the tube.

30 6. In a system as set forth in claim 2, said spring means comprising an annular series of spring fingers disposed around and extending inwardly of said socket to circumferentially contact the bearing member on the tube.

35 7. In a system as set forth in claim 1, clamp means on said mounting means at the input wave guide conductor and operative upon said adjustable means for maintaining the latter in adjusted position transversely of the axis of the field.

40 8. In a system as set forth in claim 7, said input conductor having a threaded socket connected thereto around the opening; a cup covering the source end of the tube and screw means for securing the cup to the threaded socket in adjusted position.

45 9. In a system as set forth in claim 7, said source end of the tube having connector pins extending therefrom, and said mounting means including a plug base engaging said pins; a threaded socket connected to the input conductor of the wave guide means at the opening therein; and screw means for securing the base to the threaded socket in the desired position of adjustment.
